WESLEY E. COCHRAN, OF CLEVELAND, OHIO, ASSIGNOR TO THE EMPIRE BRASS MANUFACTURING COMPANY, OF CLEVELAND, OHIO, A CORPORATION OF OHIO.

LIGHTING DEVICE.

1,031,839.

Specification of Letters Patent. Patented July 9, 1912.

Application filed March 27, 1912. Serial No. 686,660.

To all whom it may concern:

Be it known that I, WESLEY E. COCHRAN, a citizen of the United States, and a resident of Cleveland, county of Cuyahoga, and State of Ohio, have invented a new and useful Improvement in Lighting Devices, of which the following is a specification, the principle of the invention being herein explained and the best mode in which I have contemplated applying that principle, so as to distinguish it from other inventions.

The present invention relates in general to lighting devices, and its particular object is the provision of a lamp fixture which is not only portable when electrically connected with a source of current, but which may also be dismantled when disconnected so that it may be conveniently packed and transported.

It is also an object of this invention to provide such a lamp device which is capable of a wide variety of adjustments.

To the accomplishment of these and related objects, the present invention, then, consists of the means hereinafter fully described and particularly pointed out in the claims.

The annexed drawing and the following description set forth in detail certain mechanism embodying the invention, such disclosed means constituting, however, but one of the various mechanical forms in which the principle of the invention may be used.

In said annexed drawing:—Figure 1 is a perspective view of a device embodying the invention; Fig. 2 is a broken vertical section of the base and arm; Fig. 3 is a central section through the arm and socket holder, and Fig. 4 is a rear perspective view of the base.

The invention provides a base 1 which may be of any desired ornamental form, but which must necessarily be readily movable. The base is provided with a cylindrical opening 2 which may be conveniently formed by providing the base with an upright post 3 through which the hole 2 may be formed. A curved arm 4 engages the aperture 2 and is slidable therethrough longitudinally of the arm, and is also rotatable therein, and it is to be understood that the arm 4 may be of any desired length so as to constitute a greater or less arc of a circle. The arm 4 is secured in any selected

position relatively to the base by means, 55 preferably of a set screw 5.

A socket 6 is adjustably mounted upon the arm 4, and this mounting is conveniently accomplished by providing the socket with a member 7 having a transverse cylindrical opening 8 through which the arm extends. The socket is thereby slidable longitudinally of the arm and also rotatable thereon, and may be secured in selected position, preferably by a set screw 9. The socket holding member 7 is also provided, near the end at which it is secured to the socket proper, with a transverse opening 10 through which the lead wires may be conveniently extended. The socket 6 carries a lamp 11, and a shade 12 which is mounted so as to be rotatable about the axis of the lamp.

It is contemplated that the base may be provided on its under side with a recess 13 in which is hinged a ring 14.

When the device is in use the base may stand upright, as shown in Fig. 1, with the ring 14 swung back into the recess 13, or the ring may be swung out and the base 80 hung thereby on a vertical wall. In either case, the arm 4 may be slid through the opening 2 to any desired position and it may be rotated into any desired angular position, and the set screw will then be thrust 85 in to secure the arm in any selected position. The socket may be slid to any desired position on the arm, and it may be rotated into any angular position on the arm and then secured in selected position by the set 90 screw 9. At the same time the shade 12 may be rotated into desired position to reflect the light in the desired direction.

It will thus be appreciated that the device of this invention provides for an almost 95 limitless series of adjustments, for when in use, for instance, on a desk, the arm may be so adjusted in the base and the socket so adjusted on the arm that the device will accommodate itself to any condition, or 100 to any desire of the user. Furthermore, it may be hung on a vertical wall in addition to its almost universal adjustment. Again it may be used as a downwardly extending lamp, as on a piano, for instance, in which 105 case the base may stand on the piano top and the arm be swung to a position the reverse of that shown in Fig. 1. The open-

ing 10 and the longitudinal opening 15 in the socket holder renders the wiring of the device a simple matter.

In addition to providing a portable lamp capable of a wide range of adjustment, the invention also provides a lamp which may be readily dismantled and transported. It is designed that the wire 16 shall be provided at its end with a connecting plug, and when this is removed from a permanent socket, the socket holder 7 may be removed from the arm and the arm be removed from the base, and all of the elements of the device may then be conveniently packed in any small receptacle so that it may be readily carried by a traveler. When it is again desired to use the lamp it may be quickly assembled, so that it is only necessary to insert the plug in a permanent socket again in order to render the lamp ready for use.

Other modes of applying the principle of my invention may be employed instead of the one explained, change being made as regards the mechanism herein disclosed, provided the means stated by any of the following claims, or the equivalent of such stated means be employed.

I therefore particularly point out and distinctly claim as my invention:—

1. In a lighting device, the combination of a movable base; an arm formed substantially on the arc of a circle and curvilinearly slidable relatively to said base; means for securing the arm to the base in selected

position; a socket slidable along the arm; and means for securing the socket to the arm in selected position.

2. In a lighting device, the combination of a movable base; an arm formed substantially on the arc of a circle and curvilinearly slidable relatively to said base, the arm being also rotatable relatively to said base on an axis transverse to the axis of the curve in which it is slidable; means for securing the arm to the base in selected position; a socket slidable along the arm and also rotatable thereon; and means for securing the socket in selected position.

3. In a lighting device, the combination of a movable base provided with a cylindrical aperture formed on an axis substantially parallel with the supporting surface of the base; an arm formed substantially on the arc of a circle and extending through said aperture, the arm being curvilinearly slidable therethrough and rotatable therein on the axis of the aperture; means for securing the arm in selected position; a socket provided with a transversely extending cylindrical aperture loosely engaging said arm, so that the socket is slidable along the arm and rotatable thereon; and means for securing the socket in selected position.

Signed by me this 25th day of March, 1912.

WESLEY E. COCHRAN.
